[57] CLAIM

The ornamental design for a dart game board, as shown and described.

DESCRIPTION

FIG. 1 is a front elevational view of a dart game board, showing my design;

FIG. 2 is a side elevational view thereof, the other side being identical;

FIG. 3 is a top plan view thereof, the bottom being identical;

FIG. 4 is a rear elevational view thereof;

FIG. 5 is an enlarged fractional top front view thereof;

FIG. 6 is a front elevational view of a second embodiment of the design in FIG. 1; and,

FIG. 7 is a front elevational view of a third embodiment of the design in FIG. 1.
